UNITED STATES PATENT OFFICE.

CHARLES B. McCALLUM, OF OAKLAND, CALIFORNIA.

MARKER.

Application filed April 3, 1923. Serial No. 629,684.

To all whom it may concern:

Be it known that I, CHARLES B. McCALLUM, a citizen of the United States, and a resident of Oakland, county of Alameda, 5 State of California, have invented a new and useful Marker, of which the following is a specification.

The present invention relates to improvements in markers designed particularly to 10 be used by carpenters for marking face and edges of boards to be fitted against abutting boards. One particular instance in which my device may be used is the fitting of the side piece of a door or window 15 casing between two end pieces or between the top piece and the floor or the base of the window. Another instance in which my device may be used is the fitting of a base board against the frame of a door. The 20 particular object of the invention is to provide means whereby the markings may be taken from the abutting piece so that a correct fitting will be obtained even if the abutting piece is not disposed at a right angle 25 to the piece to be abutted. If an ordinary square is used for this purpose and the piece to be fitted in is cut at right angles it frequently happens that the fit thus obtained is not perfect due to the fact that the 30 door opening is not exactly rectangular. When my device is used it does not make any difference whether the opening is strictly rectangular since the measure is taken from the member to which the piece to be 35 cut is to be fitted.

The preferred form of the device is illustrated in the accompanying drawing in which Figure 1 shows a plan view of the same, Figure 2 a side view, Figure 3 a 40 partial view in front elevation of a window illustrating the manner in which my device is to be used, Figure 4 an end view of the illustration shown in Figure 3, Figure 5 a further illustration showing the use of 45 my device in a different situation, Figure 6 another view illustrating the use of my device in connection with a base board to be fitted, Figure 7 a perspective view of a modified form of a marker and Figure 8 a 50 detail view showing another slight modification in my marker. While I have shown only the preferred forms of my invention in connection with certain uses for the same I wish to have it understood that various 55 changes or modifications may be made within the scope of the claims hereto attached

and that various different uses may be found for my device without departing from the spirit of the invention.

In its preferred form my marker (1) 60 comprises a rectangular plate (2) having parallel front and rear edges (3) and (4) and having flanges (6) extending preferably at right angles from the side edges. The front edges (7) of the flanges are 65 parallel to one another and preferably arranged in the perpendicular plane of the front edge (3) of the plate. The rear ends (8) of the flanges preferably project beyond the rear edge (4) of the plate so that 70 the rear edges (8) which are parallel to one another are disposed rearwardly of the rear edge (4) of the plate by an equal distance.

The proper use of my device is illustrated 75 in Figures 3 to 6. Assuming that in a window frame the stool (9) and the top member (11) have been secured in their respective positions and that it is now desired to fit the side pieces (12). As illustrated in Figure 5 the side piece to be fitted is first set on end on the stool (9) in the manner illustrated in Figure 5 and my marker is placed over the side casing with its rear edge (4) pointing downwardly and 80 its two flanges (6) resting on the stool (9). Since the rear projections of the two flanges (6) are of equal length a pencil line drawn along the rear edge (4) of the plate will be exactly parallel to the surface of the 85 stool no matter whether the angle between the stool and the side piece (12) is an exact right angle or not. The side piece is then cut along this line and placed on the stool in the manner illustrated in Figure 90 95 3 with the top end of the side piece overlapping the top member (11) of the window casing. The marker then is again placed over the side piece with its front edge (3) in line with the lower edge (13) of the member (11) and with the front edges (7) of the flanges (6) bearing on said lower edge. A pencil mark drawn along the line 100 105 3 will then be in exact alignment with the bottom edge (13) of the top member (11) and if the side view (12) is cut along this line an exact fit will be obtained irrespective of the angle that may exist between the side piece (12) and the top member 110 (11).

If in marking the side piece in the manner described a sharp pencil is used the fit

obtained may not be sufficiently tight to allow the side casing to be sprung into place in the manner desired by most carpenters and to cause the side piece to be 5 slightly longer a pencil with a dull point may be used which draws a line a slight distance away from the edge of the marker or a modified form of marker such as illustrated in Figure 8 may be used. In the 10 latter case the front edges (14) of the flanges (16) form an angle with the upper edges (17) of the flanges slightly under 90° which will cause the front edge (18) of the marker to slightly project beyond the lower 15 edge of the top member (13) so that the side piece (12) will be slightly longer if cut along said line and has to be sprung into its place whereby its bottom and top edges are forced into closer contact with 20 the window stool and the top casing member (11).

In Figure 6 is illustrated the use of my marker in connection with a base board (19) to be fitted against the side piece (21) of a 25 lower casing.

The marker shown in Figure 7 is constructed along similar lines but differs from

that shown in Figures 1 and 2 in so far as the flanges (22) are turned inwardly as shown at (23). The object of this arrangement is to prevent the sticking out of sharp edges when my marker is lying on the floor and to prevent accidental injury to the person using the same. 30

Since the plate (2) is rectangular in form 35 it will be readily seen that the same may be used as an ordinary square.

I claim:

1. A marker of the character described comprising a plate having straight edges, 40 oppositely disposed spaced flanges on the plate having portions at one end projecting an equal distance beyond one edge of the plate and having their opposite end edges terminating flush with the other edge of the 45 plate.

2. A marker of the character described, comprising a plate having side flanges thereon presenting parallel front edges extending from the front edge of the plate and forming 50 an angle of less than 90 degrees with the top edges of the flanges. 50

CHARLES B. McCALLUM.
